Inventor
G. H. Lathrop
Right Attorney

UNITED STATES PATENT OFFICE.

G. W. LATHROP, OF WEEDSPORT, NEW YORK.

EXHAUST-PIPE OF LOCOMOTIVE-ENGINES.

Specification of Letters Patent No. 30,976, dated December 18, 1860.

To all whom it may concern:

Be it known that I, GEORGE W. LATHROP, of Weedsport, in the county of Cayuga and State of New York, have invented a new 5 and useful Improvement in Adjusting Variable-Exhaust Nozzles; and I do hereby declare that the following is a full, clear, and exact description of the same, reference being had to the accompanying drawings, forming a part of this specification, in 10 which—

Figure 1 is a transverse vertical section showing the smoke arch, variable exhausting apparatus and the steam pipes. Fig. 2 15 is a horizontal section of the same. Figs. 3 and 4 are longitudinal sections of the same, and Fig. 5 is a front end view of the whole apparatus; the head of the smoke arch being removed.

20 Similar letters of reference, in each of the several figures indicate corresponding parts.

The nature of my invention consists, first, in the combination of an adjustable beveled 25 guide flange or lug and adjusting rods which extend out beyond the front of the smoke arch, with the seat and stationary beveled guide lug of the exhaust pipes, and the slide that carries the variable exhaust 30 nozzles, substantially in the manner hereinafter described. The design of this part of my invention is to enable the engineer, from the outside of the arch, to relieve the slide which carries the variable ex- 35 hausting nozzles, whenever the same becomes set or stuck fast on its seat. The sticking of the nozzle slide has always been the greatest difficulty attending the use of variable sliding exhaust nozzles, and there- 40 fore my improvement is of importance.

Second, in combination with exhaust pipes which branch out toward the sides of the smoke arch and terminate in a slide seat that runs across the arch, my invention consists in 45 the combined arrangement of a slotted link that takes hold of the remotest end of the nozzle slide, a vertical rod, two horizontal crank arms—set at right angles to one another, and a horizontal longitudinal lever, 50 substantially as hereinafter described. The first design of this part of my invention is to afford more room in the rear end of the arch for the steam pipes, and thus obviate the necessity of foreshortening the exhaust 55 pipes in order to get them under the steam pipes, and then adding to their length by

placing what is termed a petticoat pipe (which destroys the natural draft of the locomotive), above them. These difficulties are obviated by setting the seat of the nozzle 60 slide across the chamber of the smoke arch and near the front end of the same, and thereby leaving plenty of room in rear or beyond it for the main and branch steam pipes. If the nozzle slide were employed 65 within an arch after the manner shown in Espenschade's patent of 1854, to wit, longitudinally with the chamber of the arch, the nozzles would have to be placed so near the bottom of the smoke arch that with outside 70 connected engines, there would necessarily be formed almost a square corner where the pipes intersect one another in order to get them under the nozzles. Such a square corner causes a very heavy back pressure on the 75 piston of the engine, and its avoidance by my arrangement does away with another serious difficulty attending the working of sliding variable exhaust nozzles. Another design of the second part of my invention is 80 to give a more direct thrust or pull upon the slide that carries the nozzles, than is obtained by other arrangements. The slotted link by taking hold of the extreme rear end of the nozzle slide, moves the slide without hardly 85 any deflection from a straight line.

To enable others, skilled in the art, to make and use my invention, I will proceed to describe its construction and operation.

A, is the smoke arch. B, the main supply steam pipe, and C, C, the branch steam pipes leading to the engine cylinder.

D, D, are the exhaust or waste steam pipes constructed and arranged to stand obliquely within and across the chamber of 95 the smoke arch, and to intersect one another near the center of said chamber and to terminate in a circular neck on which is mounted an oblong seat E, running across the chamber of the arch, all as represented. 100

F, is a stationary flange or lug raised on the rear edge of the seat and G, is a similar adjustable flange or lug arranged on the front edge of the seat; the inner faces of these flanges are beveled so that the two 105 form a dovetail shaped guide way for the nozzle slide to move in.

The flange G, is attached fast to the inner ends of two horizontal screw rods I, I, which extend from the front of the arch to 110 seat E, and screw into the latter, as represented. The outer ends of the rods are

made square so that a wrench may be applied to them when it is necessary to relieve the nozzle slide by causing the flange G, to recede from the said slide.

- 5 J, is the slide which carries the variable exhaust nozzles M, M. This slide is beveled on both of its edges so as to match the bevels of the flanges or lugs F, G. It will be observed that the bevel of the slide and flanges 10 is such that when the flange G, is adjusted, the exhaust nozzle slide has not only a freedom of movement on its seat, but also has a chance to move up and down to a certain extent.
- 15 K, is the slotted connecting link—it encircles the exhaust nozzles and is fastened loosely by a pivot a, to the most remote part of the nozzle slide in order that very little deflection, in the slide, from a straight line 20 shall take place. The other end of this link is fastened loosely by means of a pivot b, to a horizontal crank arm c, of a vertical rock shaft d, one end of said shaft resting on a bracket e, within the smoke arch, and the 25 other end extending out through the top of the smoke arch and having a horizontal crank arm f, attached to it. To the crank arm f, a notched adjusting lever L, running longitudinally with the smoke arch, is pivoted as represented.

30 The exhaust nozzles, in my arrangement, regulate the escape of waste steam in the ordinary manner, viz:—by sliding a large

or small nozzle over the circular hole inclosed by the neck of the waste steam or 35 exhaust pipes, accordingly as the necessities of the case may demand.

What I claim as my invention and desire to secure by Letters Patent, is—

1. The combination of an adjustable beveled guide flange or lug G, and adjusting rods I, I, which extend out beyond the front of the smoke arch A; with the seat E, and stationary beveled guide lug F, of the exhaust pipes D, D, and the slide J, that carries the variable exhausting nozzles M, M, substantially as and for the purposes set forth.

2. In combination with exhaust pipes D, D, which branch out toward the sides of the smoke arch and terminate in a slide seat E, that runs across the arch, I claim the combined arrangement of a slotted link K that takes hold of the remotest end of the nozzle slide J, a vertical rod d, two horizontal 50 crank arms c, f, set at right angles to one another, and a horizontal longitudinal lever L, substantially as and for the purposes set forth.

The above specification of my improvement in adjusting variable exhausts signed by me this 18th day of October 1860.

GEO. W. LATHROP.
